UNITED STATES PATENT OFFICE.

VINCENZO BENEDETTI, OF PALISADE, NEW JERSEY.

DESIGN FOR A SHOE-RETAINER.

53,233.

Specification for Design.

Patented Apr. 29, 1919.

Application filed November 11, 1918. Serial No. 262,079. Term of patent 7 years.

To all whom it may concern:

Be it known that I, VINCENZO BENEDETTI, a citizen of the United States, and a resident of Palisade, in the county of Bergen and State of New Jersey, have invented a new, original, and ornamental Design for Shoe-Retainers, of which the following is a specification.

Reference is to be had to the accompanying drawings in which the figure is a perspective view of a shoe retainer arranged in accordance with the present invention and shown as in service on the human foot and shoe thereon, said foot and shoe being indicated by broken lines.

I claim—

The ornamental design for a shoe retainer as shown.

VINCENZO BENEDETTI.
